W. C. TRACY

ORE CLASSIFYING TABLE

Original Filed March 27, 1924

Fig. 1

UNITED STATES PATENT OFFICE.

WARREN C. TRACY, OF LOS ANGELES, CALIFORNIA.

ORE-CLASSIFYING TABLE.

Application filed March 27, 1924, Serial No. 702,231. Renewed January 5, 1926.

To all whom it may concern:

Be it known that I, WARREN C. TRACY, a citizen of the United States, residing at Los Angeles, in the county of Los Angeles, 5 State of California, have invented a new and useful Ore-Classifying Table, of which the following is a specification.

This invention relates to ore classifying tables and is more particularly directed to 10 such a table having a new and novel arrangement of riffles or grooves for the purpose of separating the very fine portions of the valuable ores from the tailings.

Ore classifying tables as heretofore designed have had riffles or grooves substantially V-shaped cut in the surface of the table or in the covering of the table, at an angle to the vertical plane of the edge of the table. An ore classifying table with 15 20 riffles of this sort has proven satisfactory for the separation of the coarse heavy ores from the tailings, but a great deal of the very finely divided valuable ores, such as copper, silver, gold and lead, have passed 25 with the tailings over such tables and been discharged in waste.

This invention relates primarily to a new form of groove or riffle for the surface of the table, which groove or riffle has one vertical edge up which the water and ore are caused to climb when traveling over the table. The opposite edge of the riffle is slanted so that the ore and water may slide 30 into the riffle and thereafter the water will climb over the vertical edge of the riffles and pass out from the table with the tailings; also this invention relates to a manner of direction of a second set of grooves or riffles cut in the above manner, which 35 40 grooves are cut at the upper end of the table parallel to the plane of the vertical edge of the table.

An object of this invention may be to provide a set of grooves parallel to the edge 45 of the table and having inter-communicating veins for the purpose of separating the valuable ores from the tailings at the top of the table.

An object of this invention may be to 50 provide grooves or riffles of the nature heretofore described for the purpose of obtaining a complete separation of the fine portions of the valuable ores from the tailings.

Other objects and advantages of this invention will be apparent from the following 55 detailed description of a preferred embodiment

ment thereof, as set forth in the accompanying drawings.

In the drawings:

Figure 1 is a plan view of an ore classifying table embodying this invention, showing the feed trough partly broken away. 60

Fig. 2 is a side elevation partly in section of the ore classifying table illustrated in Figure 1. 65

Fig. 3 is a sectional end elevation taken substantially on the line 3-3 of Figure 1 and illustrating the form of the riffles.

Fig. 4 is an enlarged fragmental end elevation of the top of the table, particularly 70 setting forth the form of these riffles.

The table top is generally indicated at 1 and is mounted on or loosely supported by any suitable form of supports 2. Means to reciprocate the top of the table are illustrated at 3, which means may be in the form of an eccentric yoke 4 connected to the table top 1, as illustrated at 5. Flexible means such as the spring 6 connects the eccentric yoke 4 to the table top 1. The eccentric 75 mechanism is driven from any suitable source transmitting power to the belt pulley 7.

At the lower or front edge of the table there is provided a trough 8 to receive the 85 water and tailings from the table top 1. A trough 9 is provided at the far end of the table for receiving the ore separated from the tailings.

The material to be classified is first finely 90 ground and admitted into a form of hopper 10 which receives water from any suitable source, as illustrated at 11. A trough 12 is connected to the member 10 and has a number of gate valves 13 positioned upon the 95 upper end thereof so that the ore and the water are carried out toward the back edge 14 of the table top 1. The table top 1 is faced with any suitable material 15, which material 15 may be linoleum, leather, or like 100 material.

Riffles 16 having a vertical side or edge 17 and a sloped edge 18 are cut in the table top at an angle to the plane of the edge of the table, preferably diverging from the top upper edge at a slight angle toward the bottom or lower edge. A second series of riffles 19 of the same form as the riffles 16 are cut at the upper edge of the table top cover 15 substantially parallel to the vertical plane of 110 the edge of the table. A number of inter-communicating veins or riffles 20 are cut be-

tween the riffles 19 so that the valuable ores will work their way, due to their density and to the reciprocation of the table top 1, to the back edge 14 of the table top. These ores, being of greater gravity than the tailings, will tend to travel in that direction with this manner and form of grooves, making a very complete recovery of the very fine ores, such as copper, silver, gold and lead 10 from the tailings.

Valuable ores of coarser granular construction are recovered in the riffles 16 and travel along the riffles 16 to the edge of the table and are discharged into the trough 9, 15 where they may be collected and saved for separation of the ores and smelting or the like; it being understood that the table top 1 is slanted or sloped from the upper edge 14 to the lower edge so that the water and 20 tailings will travel across the table and be carried away in the trough 8. A jack or suitable means may be provided at or under the upper edge 14 of the table top 1 to vary this angle of slope, as the particular ore 25 may require.

In order to recover the slime containing considerable other valuable ores, applicant has discovered that by extending a pair of cords 21 diagonally across the table, as 30 illustrated in Figure 1, the slime will be removed from the top of the water flowing across the top of the table and will be diverted by the cords 21 into the trough 9 or other suitable slime recovering apparatus 35 which may be embodied in connection with this ore classifying table. It will be understood that the cords 21 are raised from the table to a proper height to ride on the surface of the water traveling across the table 40 top 1.

Having fully described a preferred embodiment of this invention, it is to be understood that I do not wish to be limited to the exact construction, form or shape of the 45 riffles heretofore set forth, which may obviously be varied within the spirit of this invention, as set forth in the appended claims.

I claim:—

50 1. An ore classifying table of the class described comprising a table top, supports for the table top, means for reciprocating the table top in relation to the supports, a cover for the said table top, there being 55 riffles in the table top at an angle to the direction of reciprocation of the table top,

there being riffles in the table top substantially parallel to the direction of reciprocation of the table top, and inter-communica- 60 tive veins or riffles in the table top between the said parallel riffles.

2. An ore classifying table of the class described comprising a table top, supports for the table top, means for reciprocating the table top in relation to the supports, a 65 cover for the table top, there being riffles in the table top cover at an angle to the direction of reciprocation of the table top, there being riffles at the upper edge of the table top covering substantially parallel to 70 the direction of reciprocation of the table top, said riffles having a vertical side and a sloping side substantially as and for the purposes described, and veins or riffles for communication between the said parallel 75 riffles substantially as heretofore set forth.

3. In an ore classifying table of the class described, the combination of a table top, supports for the table top, means for reciprocating the table top in relation to the supports, a cover secured to the said table top, riffles cut in the table top cover at an angle to the vertical plane of the edge of the table, riffles cut in the table covering at the upper edge of the table substantially 80 parallel to the vertical plane of the edge of the table, and cords extending diagonally across the table top at a distance above the table top substantially as and for the purpose described. 85

4. In an ore classifying table of the class described, the combination of a table top, means for imparting a reciprocatory motion to the table top and cords extending diagonally across the table top at a distance above 90 the table top. 95

5. An ore classifying table of the class described, comprising a table top, a covering secured to the table top, means for supporting the table top, means for imparting a 100 reciprocatory motion to the table top, there being riffles in the table top at an angle to the direction of reciprocation of the table top, riffles in the table top substantially 105 parallel to the direction of reciprocation of the table top, and cords extending diagonally across the table top at a distance above the table top.

Signed at Los Angeles, California, this 18th day of March, 1924.

WARREN C. TRACY.
